UNITED STATES PATENT OFFICE.

JOSEPH SAWDON, OF QUINCY, ILLINOIS.

DUPLEX ENVELOPE.

Application filed July 11, 1921. Serial No. 433,665.

The invention relates to duplex envelopes of that kind in which one compartment is provided for first class mail matter, such as a letter, and in which another compartment, 5 preferably larger and more roomy, is provided for mail matter less than first class, whereby the entire envelope, with both kinds of mail matter therein, and with separate postage attached for each class of mail matter, 10 will be delivered as one piece of mail, thereby avoiding separate deliveries of the letter and things mentioned in the letter, and at the same time avoiding the necessity of paying first class postage on the enclosures 15 as well as on the letter itself.

Generally stated, the object of the invention is to provide an improved construction and arrangement whereby the entire duplex envelope is made from a single paper blank.

20 It is also an object to provide certain details and features of construction tending to increase the general efficiency and the desirability of a duplex envelope of this particular character.

25 To these and other useful ends the invention consists in matters hereinafter set forth and claimed and shown in the accompanying drawings in which—

Figure 1 is a front or face view of a duplex envelope embodying the principles of 30 the invention.

Figure 2 is a view of the back or rear side of said envelope, with a portion broken away to bring certain other portions into view.

35 Figure 3 is a vertical section on line 3—3 in Figure 2.

Figure 4 is an inside view of the single paper blank from which the entire duplex envelope is made.

40 Figure 5 is a perspective showing said blank partially folded.

Figure 6 is a horizontal section on line 6—6 in Figure 1.

As thus illustrated the invention comprises a rectangular paper section 1 which forms the front wall of the envelope, and which is provided at one end with an adhesive flap 2 and at the other end with a non-adhesive flap 3, the latter flap being preferably larger than the other flap. The rectangular section 4 forms the back or rear wall of the envelope and is provided with suitable adhesive 5 along the edge thereof. The rectangular section 6 forms the inner wall of the smaller compartment of the envelope, and is provided at each end thereof with

adhesive 7 for attachment to the inner surface of the wall 1 when the blank is folded. The section 6 has a flap 8 provided with adhesive 9, and this flap extends through the opening formed by the slit 10 in the wall 1, as shown in Figure 1, when the blank is folded. The slit 10 is so formed that a flap 11 is formed which hangs inside of the wall 6, and if desired a strip of adhesive paper 12 may be applied to the inner surface of the flap 11 and the inner surface of the wall 6, as shown in Figure 2, to strengthen the construction, but this strip may be omitted, and whether it is used or not the entire duplex envelope is practically formed from the single paper blank. After the wall 6 is folded and secured in place, the wall 4 is then folded over and secured by its adhesive 5 to the wall 6 and to the exposed portions 13 of the front wall 1, thus leaving the larger compartment still open at each end. Then the flap 2 is folded over and secured by its adhesive to the back of the envelope. The flap 3 is left loose and may be secured in place by a fastener 14, after the third or fourth class mail matter is inserted in the larger compartment. After the letter is inserted in the smaller compartment formed between the walls 1 and 6, the flap 8 is then secured by its adhesive 9 to the front of the envelope. The smaller compartment can be defined or outlined by the lines 15 on the front of the envelope, if this is desired. A place is indicated at 16 for the first class postage for the letter, and another place is indicated at 17 for the stamps necessary for the third or fourth class mail matter, or for any other mail matter less than first class. If desired, the arrow 18 can be applied as shown, to indicate where the letter is inserted, and the hand 19 can be applied as shown to indicate where the letter is found in the envelope structure.

It will be understood, of course, that the larger compartment can be accessibly closed in any suitable or desired manner, but this is preferably done by means of a flap which is integral with the front wall of the envelope. The front of the envelope as a whole is, of course, the side upon which the address is attached and upon which the postage is applied. The important thing, of course, is that the two compartments are permanently fastened together while being transmitted through the mails, as it makes little difference, in some ways, whether the

compartments are together before being deposited in the mails, or after the envelope is opened by the person to whom it is addressed, for the main object is to prevent separation of the first class mail matter from the third or fourth class mail matter while they are being transmitted through the mails. The integral formation of the walls of the two compartments, however, means that the two compartments are never separated after the blank is folded and reduced to envelope form, but the construction whereby the duplex envelope is formed from a single paper blank may be of any suitable character, as the invention is not limited to the exact construction shown and described.

It will be seen that the flap 8 is on the address side of the envelope, and the address side of an envelope is the face or front thereof. The flap 8 is immediately above the space or place for the address, and is a distance below the upper edge of the envelope. Also, the ends of the envelope extend a distance beyond the ends of the small compartment, at the right and the left of the latter, and the small compartment is within the area of the large compartment, as it does not extend outside of such area at any point. Sealing of the small compartment, in the manner explained, does not in any way seal or close the large compartment, as the two compartments are independent of each other, notwithstanding that the walls of the two compartments are formed from a single blank as explained. It will be seen that when the flap 8 is sealed in place on the address side of the envelope, the small compartment is thereby closed everywhere against access thereto from the outside of the envelope, as on the outer surface of the envelope the slot 10 is the only means of access to the small compartment. Therefore, when the small compartment is closed, there is nothing on the face or address side of the envelope to permit access to the small compartment. More specifically, of course, when the section 6 is glued at its ends, as at 7, it follows that the small compartment is absolutely sealed everywhere, when the flap 8 is secured in place, so that no access may be had to this small compartment either outside or inside the envelope. When the envelope is made up, it will be seen that it only comprises three walls, or three thicknesses of paper, as the wall 6 is a single wall interposed between the two compartments, and is common to both compartments. Therefore, the matter inserted in the small compartment is necessarily inserted edgewise, against the wall of the larger compartment, and the contents of the small compartment necessarily occupies this position against the wall of the large compartment before any attempt is made to seal the small compartment. When

the envelope is ready for use, thus formed from a single blank, there is only a single thickness between the two compartments, thus minimizing the amount of paper required, and the thickness of the envelope. It will be seen that the outside wall of the small compartment extends the full length of the envelope in order to provide necessary wall material for the large compartment as well. By this is meant that at least some portion of the wall extends the full length of the envelope. In other words, it is better to have the outside wall of the small compartment formed by wall material which is necessary, at least to some extent, as wall material for the large compartment as well, as this simplifies the cutting of the blank and is more satisfactory in the manufacture of duplex envelopes of this character, and is more satisfactory in use. It will be seen, therefore, that the smaller compartment is formed in part by the section 6 which is of less area than the envelope, and that the smaller compartment is sealed by the flap 8 which is spaced a distance from all four edges of the envelope, and which is sealed against the face or address side of the envelope, after something has been inserted in the smaller compartment.

What I claim as my invention is:

1. A duplex envelope made from a single blank and having a relatively large and a relatively small compartment, said relatively small compartment being formed by a sheet applied to the inner surface of the front wall of the envelope, said sheet having a loose flap, said envelope having a slot in its front wall through which said flap projects outwardly, so that after the letter is inserted through said slot into the relatively small compartment the flap may then be sealed by causing it to adhere to the outer surface of the envelope, said small compartment being disposed adjacent to the lower edge of the large compartment, and an inner retaining strip back of said flap to secure the upper edge portion of the sheet to the front wall of the envelope.

2. A compartment envelope comprising a front section having a slot, a back section, a partition flap integrally connected to one of said sections and forming a compartment on the inner face of the front, and a sealing flap on the partition flap, the sealing flap being inserted through a slot in the front.

3. A duplex envelope comprising a relatively large rectangular compartment for printed matter, or for other mail matter less than first class, and a relatively small letter compartment on the front of said large compartment, so that one address applied to the small compartment is sufficient for both kinds of mail matter, with a flap on the rear side or back of the envelope.

lope for accessibly closing the large compartment, and a flap on the face or front side of the envelope for sealing the small compartment, all formed from a single 5 paper blank.

4. A duplex envelope comprising means to form a relatively large rectangular compartment, and means including a section of less area than the envelope to form a relatively 10 small compartment at the address side of said large compartment, with said small compartment sealed everywhere against access thereto from outside the envelope except where this small compartment is left 15 open at one outside edge thereof, with the outside wall of the small compartment extending the full length of the envelope to form wall material for the large compartment as well, and with only a single thickness 20 between the one compartment and the other, whereby matter inserted in this small compartment is against the wall of the large compartment so that in use one address applied to the small compartment is sufficient, with a flap on the envelope for closing 25 the large compartment, and a flap on the address side of the envelope and spaced a distance from all four edges thereof for sealing the small compartment against access thereto 30 from outside the envelope, all formed from a single paper blank.

5. An envelope structure as specified in claim 4, said flap for sealing the small compartment being disposed immediately above the place for the address and a distance 35 below the upper edge of the envelope and it being necessary to break or detach the sealing flap to remove the contents thereof.

6. An envelope structure as specified in claim 4, having means to outline the smaller compartment on the address side of the envelope, on the said wall which extends the full length of the envelope, with the place for the address within said outline, 40 and with said flap for sealing the small compartment disposed immediately above the place for the address and a distance below the upper edge of the envelope, so that the contents of the envelope are inserted 45 horizontally in one end of the large compartment and downwardly at the top of the small compartment and whereby sealing of the small compartment does not in any way 50 seal or close the large compartment.

55 7. In a duplex envelope, providing a plu-

rality of compartments, including a smaller compartment within the area of a larger compartment, a sealing flap disposed a distance from all four edges of the envelope, for sealing the smaller compartment, said 60 flap and the walls of the larger compartment being integrally connected together, said flap being sealed upon the face or address side of the envelope, this face or address side being smooth and seamless except for the provision of said flap thereon. 65

8. In a duplex envelope, providing a plurality of compartments, including a smaller compartment within the area of a larger compartment, a sealing flap disposed a distance from all four edges of the envelope, for sealing the smaller compartment, said 70 flap and the walls of the larger compartment being integrally connected together, and an integral flap for the larger compartment, the front wall of the envelope upon which the address is placed forming the outer wall of the smaller compartment, so that the smaller compartment is inside the 75 larger compartment. 80

9. A duplex envelope composed of a section of material folded on itself to afford two outer walls and an intermediate wall, the terminal portion of the intermediate wall constituting a flap, and one of the outer 85 walls being provided with a slot through which the flap is projected in position to be sealed against the outer surface of said wall, the remaining outer wall being sealed along a plurality of its edges to afford, in conjunction with the slotted wall and intermediate wall, two compartments. 90

10. A duplex envelope composed of a section of material folded on itself to afford two outer walls and an intermediate wall, 95 the terminal portion of the intermediate wall constituting a flap, and the outer wall which is immediately connected to the intermediate wall being provided with a slot 100 through which the flap is projected in position to be sealed against the outer surface of said wall, the remaining edges of said intermediate wall being sealed against the proximate inner surface of said slotted outer wall, and the remaining outer wall 105 being sealed around two of its free edges to afford an enclosure for inferior class mail matter.

JOSEPH SAWDON.
